H. T. BRENNER

Des. 172,699

CANDLESTICK

Filed Sept. 1, 1953.

FIG. 1.

FIG. 2.

INVENTOR.

BY

UNITED STATES PATENT OFFICE

172,699

CANDLESTICK

Howard T. Brenner, Providence, R. I., assignor to
Gorham Manufacturing Company, Providence,
R. I., a corporation of Rhode Island

Application September 1, 1953, Serial No. 26,650

Term of patent 7 years

(Cl. D48—2)

To all whom it may concern:

Be it known that I, Howard T. Brenner, a citizen of the United States of America, residing at 491 Spring Green Road, city of Providence, State of Rhode Island, have invented a new, original, and ornamental Design for Candlestick, of which the following is a specification, reference being had to the accompanying drawings, forming a part hereof.

Fig. 1 is a side elevational view of a candlestick, showing my new design; and

Fig. 2 is a top plan view thereof.

I claim:

The ornamental design for a candlestick, as shown.
